UNITED STATES PATENT OFFICE

HARRY MEACHEM, OF TEANECK, NEW JERSEY, ASSIGNOR TO TODD DRY DOCK, ENGINEERING & REPAIR CORPORATION, OF BROOKLYN, NEW YORK

DAMPER CONTROL MEANS FOR FURNACES

Application filed April 15, 1931. Serial No. 530,178.

This invention relates to furnaces employing a blower to create the primary air supply, and having induced or secondary air supply means, which may be in the form of an air box or hollow front whose inlet is controlled by a damper, and the purpose of my improvement is to provide automatic means for operating the damper so that the supply of air to the air box may be shut off when the blower ceases to function and said damper may be caused to open when the blower starts up.

With an automatically controlled furnace it has been found that when the thermostat or pressurestat has shut off the flame and the damper is left open cold air is induced into the fire box and rapidly cools off the furnace, consequently shortening the shut down period of the flame. By means of an automatic damper control which will eliminate the cold air the shut down period will be lengthened and considerable economy of fuel will result.

Therefore my invention consists in the provision of damper control means whose opening action is a function of the pressure exerted by the blower, and whose closing action is performed by gravity means which become operative upon cessation of blower pressure.

In other words the damper is counterbalanced by a weight which tends to hold the damper in its closed position, and means are provided whereby the pressure of the blower is applied to overcome the gravity influence of the weight and to open the damper.

Other features and advantages of my invention will hereinafter appear.

In the drawings:

Figure 1 is a front view of a furnace, having an air box, with a damper, and provided with a blower, also having my improved damper control means.

Fig. 2 is a top plan view of Fig. 1, and

Fig. 3 is a detail of the operating cylinder, piston and weight.

In the drawings let 1 indicate the throat of a furnace which may be equipped with suitable fuel burning means, (not shown) and let 2 indicate a hollow-front, or air box, hav-

ing the damper 3 to control the inlet for secondary air supplies.

At 4 there appears a blower, which is operated by a motor 5, for delivering the primary air supply under pressure to the fuel burning means.

The parts thus far referred to are of usual character.

Attached as to the blower casing is a vertically disposed cylinder 6, having its upper end open, and in which is placed a piston 7 that has a rod 8 pivoted thereto.

The bottom of cylinder 6 is connected, as by a pipe 9, with the blower casing, so that when the blower is operating, pressure therefrom will pass to the cylinder to raise the piston therein.

A lever 10, fulcrumed as at 11 in a fixed support 12, is pivotally connected at one end to rod 8 as at 13, said lever engaging at its other end, as at 14, with one end of a pitman 15, whose other end engages a crank 16 that operates the damper.

The pitman 15 is in two parts, connected by a turnbuckle 17 for its adjustment in length.

A weight 18, carried by rod 8, normally forces the piston 7 to the bottom of cylinder 6, as appears in Fig. 1, in which position of the piston the lever 10, through the pitman 15 and crank 16, holds the damper in its closed position. In Fig. 1 the damper is shown closed in dotted lines, and open in dot and dash lines.

But when the blower is operating and pressure is introduced into the cylinder 6 through pipe 9, thereby the piston 7 is forced upwardly, as appears in Fig. 3, and in this action the damper is moved to its open position for the supply of secondary air to the air box and furnace.

An adjustment screw or stop 19, threaded through a support 20 therefor at the top of cylinder 6, may be employed to regulate the extent of the piston rise and thus the degree of opening accorded the damper.

Variations within the spirit and scope of my invention are equally comprehended by the foregoing disclosure.

I claim:

1. The combination with a furnace having induced air supply means, a damper therefor, and a blower to supply primary air, of a cylinder located in fixed relation to said furnace, a piston in said cylinder, a piston rod, adjustable connecting means between said rod and damper, a weight carried by said piston to counterbalance said damper and normally close it while holding the piston depressed, communicating means between said blower and cylinder whereby pressure from the blower will raise the piston and cause the damper to open, and adjustable means for regulating the stroke of the piston.
- 10 2. The combination with a furnace having induced air supply means, a damper therefor, and a blower to supply primary air, of a cylinder located in fixed relation to said furnace, a piston in said cylinder, a piston rod, adjustable connecting means between said rod and damper, a weight carried by said piston to counterbalance said damper and normally close it while holding the piston depressed, and communicating means between said blower and cylinder whereby pressure from the blower will raise the piston and cause the damper to open.
- 20 3. The combination with a furnace having induced air supply means, a damper therefor, and a blower to supply primary air, of a cylinder located in fixed relation to said furnace, a piston in said cylinder, a piston rod, connecting means between said rod and damper, a weight carried by said piston to counterbalance said damper and normally close it while holding the piston depressed, communicating means between said blower and cylinder whereby pressure from the blower will raise the piston and cause the damper to open, and adjustable means for regulating the stroke of the piston.
